DEVICE FOR REMOVING WORN BRAKE LININGS

Herbert D. Kelley and Willis E. Knott, Akron,
Ohio, assignors to Quality Tool & Machine,
Akron, Ohio, a partnership

Application April 5, 1950, Serial No. 154,088

4 Claims. (Cl. 164—38)

1

This invention relates to apparatus for removing worn brake linings adhesively adhered to brake shoes.

The current practice of fastening linings to brake shoes is to bind the two together by some suitable adhesive. This invention provides an efficient but inexpensive device for removing linings so adhered to a brake shoe after the linings have been worn down to the point where they are no longer useful. The device is exceedingly simple in structure and in its mode of operation.

The device includes means for supporting a worn brake shoe and a knife adapted for cutting the worn lining from the shoe. Means is provided to produce relative movement between the shoe and the knife so that the worn lining is cut from the shoe. In the preferred device the shoe-supporting means is rotated so that the brake shoe is moved relatively to the cutting edge of the knife. The shoe-supporting means is preferably rotated manually by a suitable handle although a motor or the like may be provided for this purpose. In the preferred device designed for manual operation, connected between the handle and the shoe-supporting means is a mechanism such as a gear train or the like to increase the mechanical advantage of the device. The distance between the knife and the center of rotation of the shoe-supporting means may be changed from time-to-time in order for the device to accommodate shoes of different sizes. The knife is pivotally supported so that the angle at which it is presented to the surface of the brake shoe may be adjusted.

In the preferred shoe-supporting means only the forward end of a brake shoe is anchored to the supporting means to cause the brake shoe to rotate with the supporting means, the balance of the shoe being supported on the supporting means but not being fastened thereto.

The invention will be further discussed in connection with the accompanying drawings which show a device designed for manual operation and illustrate the manner of using it.

Fig. 1 is a front elevation of the device in use;

Fig. 2 is a view of the device taken from the right side of Fig. 1 (omitting the brake shoe and lining shown in Fig. 1);

Figs. 3 and 4 are cross-sectional views taken on the lines 3—3 and 4—4 respectively of Fig. 1;

Figs. 5 and 6 are elevational views of the preferred gear mechanism taken on the lines 5—5 and 6—6 respectively of Fig. 2;

Fig. 7 is a detail of the preferred means for mounting a brake shoe on the mandrel, the view being taken on the line 7—7 of Fig. 1; and

2

Fig. 8 is an enlarged view of the knife support taken on the line 8—8 of Fig. 1.

The frame of the device is preferably a casting having two vertical, parallel plates 1 and 2 extending upwardly from a plate 3 which may be anchored to a workbench or other suitable working surface. A shaft 5 is supported between the vertical plates and it may be rotated by applying turning force to the rods 6 which extend radially outward from a hub 8 fastened on the end of the shaft which extends through plate 2. Shaft 5 operates a spur gear train located between the vertical plates which in turn rotates a mandrel 12. The mandrel supports a brake shoe 13 having worn lining material 14 to be removed from its flange portion 15. A knife blade 17 having a cutting edge at least as wide as the width of the flange is adjustably supported by a knife block 18 in the arm 19 which is integral with plate 1. In the operation of the device the knife is adjusted so that its cutting edge is quite close to the surface of the brake shoe's flange and as the mandrel moves the brake shoe's flange downwardly in front of the cutting edge of the knife the worn lining 14 is cut away from the flange. The turning force applied to the rods 6 is compounded by the gear train to turn the mandrel with the force necessary for the knife to shear the worn lining away from the brake shoe flange. Figs. 5 and 6 show a preferred spur gear train used to rotate the mandrel. (In these figures teeth are indicated only at the point where one gear is meshed with another.) The gear 22 is rigidly fastened (preferably welded) to shaft 5 so that it rotates with the shaft and is meshed with a smaller gear 23 which is rotatably mounted on a stub shaft 24 projecting from the inner surface of plate 2. Gear 23 is meshed with a gear 25 which is rotatably supported on a shaft 27 extending between the vertical plates 1 and 2. As shown in Fig. 2 these gears are mounted one below the other next to the inner surface of plate 2. Gear 28 is also rotatably mounted on shaft 27 but is next to the inner surface of plate 1. Gear 28 and gear 25 are each welded to a spacer 29 (Fig. 2) which separates these gears so that the gear 28 and gear 25 rotate together. Gear 28 is meshed with a gear 31 which is rigidly mounted next to the inner surface of plate 1 on a shaft 32. Shaft 32 is offset from the other gear shafts and it is rotatably supported between the plates 1 and 2. It extends through plate 1 and a pinion 33 (Fig. 5) is fastened to it next to the outer surface of plate 1. Gear 31 and pinion 33 are each welded to shaft 32 so that they rotate together. This pinion is meshed with a main

gear 34 which is rotatably mounted on the end of shaft 5 and held by a cap 35 which bears against the hub 36 of gear 34 and is fastened to the end of the shaft by the bolt 37. The mandrel 12 is bolted to the outer face of main gear 34 as shown in Fig. 3 and rotates with the main gear as this gear is driven by pinion 33.

Other forms of gearing may be substituted for the gearing illustrated. The gearing shown is used for manually operated models. If a motor or other power unit is to be used to operate the device it may be desirable to modify the preferred mechanism somewhat. For example the mandrel might be rigidly fastened directly to supporting shaft 5 and the shaft rotated by turning a worm engaged with a worm gear rigidly fastened to shaft 5. Any mechanism capable of providing the desired mechanical advantage may be used to transmit the force applied to the actuating means, such as the rods 6 or a motor, etc. to the mandrel.

The preferred mandrel 12 is shown in cross section in Fig. 3. The mandrel is cylindrical in shape and around its curved surface there is a peripheral groove 40 which extends radially inwardly. Several mandrels each of the same design but of different diameters will be provided for each device to accommodate brake shoes of different sizes. The curvature of the mandrel's surface will be substantially equal to the curvature of the brake shoe to be cleaned so that the undersurface of the brake shoe's flange 15 fits flat against the curved surface of the mandrel and the brake shoe's web 42 fits into the peripheral groove 40. The interior web portion 44 of the mandrel is relatively thin and fits flat against the outer surface of the main gear 34. An opening 45 at the center of the mandrel fits over the cap 35 and the gear hub 36. Lugs or bolts 47 fit through holes 48 in the web 44 and are threaded into tapped holes 49 in the outer surface of the main gear 34 to fasten the mandrel to the gear. The location of the holes through which the bolts 47 extend will be identical for each of the different size mandrels so that the mandrels are interchangeable on the device. To remove a mandrel it is merely necessary to loosen the bolts 47 and pull the mandrel off the gear hub 36. A different size mandrel is then placed on the gear hub and the bolts 47 reinserted through the holes 48 and threaded into the face of the main gear 34.

The knife block 18 which is the unit supported by the arm 19 includes a base plate 51 with a stud 52 extending perpendicularly from one side of the plate (see Fig. 8). The inner end 53 of the stud is press-fitted into the base plate and a threaded shank 54 extends from this press-fitted portion through the base plate. The base plate 51 fits into a channel 55 which is formed along the front face of the arm 19. When the base is in this channel the stud's shank 54 extends through a longitudinally disposed slot 56 which is formed through the center of the arm and also fits through a bar 57 which fits into a groove 58 formed along the back face of the arm 19 on each side of slot 56. The knife block may be adjusted to various positions on the arm by sliding the base plate back and forth in the channel 55. At any desired position on the arm the base plate 51 may be fastened rigidly to the arm by tightening a knob 59 threaded onto the shank 54 and also by tightening a bolt 60 which extends through the bar 57, through the slot 58 and is threaded into the base plate (see Fig. 4).

To adjust the knife block to a particular posi-

75

tion on the arm 19 the bolt 60 and the knob 59 are loosened and the base plate is slid along the channel to the desired position. The stud's shank 54 and the bolt 60 slide freely along in slot 56 as the base plate and bar 57 are moved back and forth in the channel. At a desired position the knob 59 is tightened by hand and then bolt 60 is tightened to anchor the base plate firmly in place. As this bolt and knob are tightened the bar 57 and the base plate 51 are drawn up tightly against their respective sides of the arm 19 so that the knife block is held securely.

The stud 52 supports a knife holder 61 to which the knife blade 17 is fastened by the bolts 63. A threaded shank 64 formed on the outer end of the stud extends beyond the side of the knife holder. A knob 65 is threaded onto this outer shank 64 and is adapted to be tightened against a washer 66 which presses against the outside edge of the knife holder and retains the knife holder on the stud. The knife holder 61 is pivotal about the stud when knob 65 is loosened. The angle at which the knife blade 17 is directed toward the mandrel is regulated by the knob screws 67 and 68 which are mounted in the bosses 69 next to the upper and lower edges of the base plate 51. Screw 67 is threaded through its boss to press against the portion of the knife holder above the stud and screw 68 is threaded through its boss to press against the portion of the knife holder below the stud. When the screws 67 and 68 are adjusted to hold the knife at a particular angle, knob 65 is then tightened against the side of the knife holder to hold it rigidly against the base plate.

The boss 69 near the upper edge of base plate 51 is provided with a projection 70, the upper surface of which is flush with the upper surface of arm 19. An indicating mark 71 (see Fig. 8) is formed on the upper surface of the projection and this mark is adapted to register with the calibrations 72 along the upper surface of arm 19 which indicate the approximate positions at which the knife block should be located for various types of brake shoes.

To operate the device a brake shoe having a worn lining to be removed is placed on the upper portion of the mandrel 12 with its web 42 extending into groove 40 and its flange 15 resting on the cylindrical surface of the mandrel. The edge of the mandrel is provided with several circumferential slots 73 located at spaced intervals. The sidewalls 74 of each slot 73 are not radial but they slant away from a radial direction so that when the mandrel is rotated to a position where the slot is adjacent knife 17 the sidewalls of the slot will slant upwardly away from the knife. In other words, they slant inwardly away from the forward end of the brake shoe which is being cleaned; they slant away from the direction in which the mandrel is rotated. The brake shoe to be cleaned is adjusted on the mandrel so that the end of the shoe that points toward the knife extends at least partially over one of the slots 73. In any conventional brake shoe there are a number of holes at each end of the web, such as the hole 75 shown in Fig. 1, and to anchor the brake shoe to the mandrel a pin 75 is inserted through one of these holes. The pin lies parallel with the sidewall surface 74 of the slot 73 in which it is fitted and as shown in Fig. 7 it projects on each side of the web and bears against the slot's upper sidewall. Only the forward portion of the brake shoe is anchored to the mandrel in this manner.

The knife block is adjusted so that the cutting

edge of the knife is sufficiently close to the flange of the brake shoe to cut away the worn lining, the knob screws 67 and 68 are adjusted to regulate the angle at which the knife blade is directed toward the brake shoe, and the knob 65 is tightened. As the mandrel is rotated by turning the rods 6 the knife blade peels the worn lining away from the flange as indicated in Fig. 1. A considerable force is required to move the brake shoe flange across the cutting edge of the knife to remove the worn lining. Due to the shape of the slot's sidewalls the pin 76 has a tendency to slide down the upper sidewall toward the bottom of the slot 73 as the pressure against the knife increases. This action of the pin 76 holds the brake shoe tightly against the mandrel.

When the mandrel has moved the brake shoe through the necessary arc for the knife to have cut away all of the worn lining, the pressure of the brake shoe against the mandrel is automatically released immediately and the brake shoe falls away from the mandrel. Another brake shoe is then placed on the upper surface of the mandrel with a pin similar to pin 76 extending through one of the holes in the forward end of the web of the brake shoe, and the same operation repeated.

The knife removes the worn lining cleanly. The frame of the device is of heavy construction to withstand the large force required to remove the lining. In the preferred device a suitable hood (not shown) will be used to enclose the gears between the plates 1 and 2 and also the main gear 34. The invention is defined in the appended claims.

What we claim is:

1. A support for a brake shoe which has a hole near one end of its web, the support having a curved outer surface and being adapted for rotation in one direction in equipment designed for removal of worn lining adhered to the brake shoe, said curvature of the outer surface of the support being the same as the flange of the brake shoe adapted to be supported thereon, a groove in said surface adapted to receive the web of said brake shoe, and several slots in the surface the backward edge of each of which slants away from the direction in which the support is adapted to rotate and is deep enough to expose said hole.

2. A support for a brake shoe which has a hole near one end of its web, the support having a curved outer surface and being adapted for rotation in one direction in equipment designed for removal of worn lining adhered to the brake shoe, said curvature of the outer surface of the support being the same as the flange of the brake shoe adapted to be supported thereon, a groove in said surface adapted to receive the web of said brake shoe, and a slot in the surface the back-

ward edge of which slants away from the direction in which the support is adapted to rotate and is deep enough to expose said hole.

3. A device for cutting a worn lining from a brake shoe to which it is adhesively adhered, the brake shoe having a hole near one end of its web, which device includes a support having a curved outer surface, said curvature of the surface of the support being the same as the flange of the brake shoe, and a groove in said surface to accommodate the web of the brake shoe, there being a slot in said surface which exposes said hole in the web and slants away from the direction in which the support is adapted to rotate, means for rotating the support in said direction which includes gear mechanism for compounding the force applied for rotation of the support, and a knife adjustably supported with its cutting edge in a plane perpendicular to the plane of rotation, which knife is adapted to cut lining adhesively secured to the brake shoe as the support is rotated.

4. A support for a brake shoe having a hole through one end thereof, which support is adapted for mounting on a rotatable member, the support providing a surface which is complementary to the curved flange of said brake shoe and is provided with a groove adapted to accommodate the web of the shoe, slot means in said surface which is adapted to engage means inserted through said hole in the brake shoe when the brake shoe is on top of the support, the backward edge of said slot means slanting away from the direction in which said rotatable means is adapted to be rotated whereby when the support is rotated so that the brake shoe is no longer on top of the support automatic downward release of the brake shoe from the support is facilitated.
